UNITED STATES PATENT OFFICE.

JACKSON D. COMSTOCK, OF CHESTER, WEST VIRGINIA.

DESIGN FOR AN AUTOMOBILE TIRE.

Application filed December 11, 1922. Serial No. 4,567. Term of patent 14 years.

To all whom it may concern:

Be it known that I, JACKSON D. COMSTOCK, a citizen of the United States, residing at Chester, in the county of Hancock and State of West Virginia, have invented a new, original, and ornamental Design for Automobile Tire, of which the following is a specification, reference being had to the accompanying drawings, forming a part hereof.

Figure 1 is a perspective view of an automobile tire embodying my invention; Fig. 2 is a side elevation of a segment thereof and Fig. 3 is a radial cross section through the tire casing.

I claim:

The ornamental design for an automobile tire as shown.

JACKSON D. COMSTOCK.
